UNITED STATES PATENT OFFICE.

LEVI BERGER, OF PHILADELPHIA, PENNSYLVANIA.

DESIGN FOR TOILET-WARE HANDLE.

SPECIFICATION forming part of Design No. 12,212, dated April 5, 1881.

Application filed February 19, 1881. Term of patent 7 years.

To all whom it may concern:

Be it known that I, LEVI BERGER, a citizen of the United States, residing at the city of Philadelphia, in the State of Pennsylvania, have invented or produced a new and useful Design for Toilet-Ware Handles; and I do hereby declare the following description to be a full, clear, and exact specification of the same, reference being had to the accompanying drawings, forming part of this specification, wherein—

Figure 1 is a front elevation, and Fig. 2 a side elevation, of my design.

My design embraces a cross-piece, A, and two approximately S-shaped pendants or arms, B B, depending therefrom and terminating in leaf or arrow-head shaped ears C C, which flare with respect to each other and have intaglio marginal lines or recesses c c. The cross-bar

channels or grooves c' between the same, being thus in cross-section of diamond shape approximately.

In an application of even date herewith, serial No. 26,596, I have illustrated certain constituent features of this design. I therefore do not here lay claim specifically to such features, but limit my design or configuration shown as a whole. 30

What I claim as my invention is—

The design for handle herein shown and described, consisting of cross-bar A and pendants or arms B, with leaf-shaped flaring terminals C, as illustrated. 35

In testimony that I claim the foregoing I have hereunto set my hand this 17th day of February, 1881.

LEVI BERGER.
